UNITED STATES PATENT OFFICE.

HOMER E. GIDDINGS, OF PITT MEADOWS, BRITISH COLUMBIA, CANADA.

RAIL-JOINT.

1,107,930.

Specification of Letters Patent. Patented Aug. 18, 1914.

Application filed November 26, 1912, Serial No. 733,718. Renewed January 24, 1914. Serial No. 814,239.

To all whom it may concern:

Be it known that I, HOMER E. GIDDINGS, a citizen of the United States, residing at Pitt Meadows, British Columbia, Canada, 5 have invented new and useful Improvements in Rail-Joints, of which the following is a specification.

The present invention relates to improvements in rail joints.

10 The primary object of the invention is to provide a joint of this character in which the rail ends will be securely held, so as to prevent the splitting, spreading or lateral displacement thereof, and that will afford a smooth joint between the rails so as to obviate the pounding of the car wheels when passing over one rail and onto another, and also that will relieve the strain upon the bolts connecting the rail ends with the joints. 15

20 Other objects and advantages will appear as the description progresses, reference being had to the accompanying drawings, in which a simple and preferred embodiment of the invention is disclosed.

25 In the drawings: Figure 1 is a perspective view of a rail joint constructed in accordance with my invention, and showing the meeting ends of the rails mounted therein, Fig. 2 is a perspective view of the base or 30 bed plate, Fig. 3 is a transverse sectional view taken approximately on the line 3—3 of Fig. 1, Fig. 4 is a perspective view of the wedge member, Fig. 5 is a perspective view of a modification, Fig. 6 is a similar view of 35 one of the side members of the joint employed in the device illustrated in Fig. 5, and Fig. 7 is a central transverse sectional view through the device illustrated in Fig. 5.

In the construction of a rail joint, I have 40 found it highly desirable to provide a bed or base plate which has simple means for securing the side or fish plates of the joint thereon, but which will render the said plates free from the bed. I therefore provide a bed 45 plate which is designated by the numeral 1, the same being of a desired length and of a width greater than the width of the base flanges of the rails which are adapted to rest upon the said bed plate. The plate 1 is constructed of some suitable metal and has its 50 longitudinal edges upset vertically as at 2 and provided with inturned flanges 2' which overlie the bed proper. The flanges 2' as well as the bed plate are provided, adjacent 55 the opposite ends of the said plate with registering notches 3 for the reception of the

securing spikes. The upset portions 2, as well as the flange 2' and the base 1 are cut away to provide slots 4, the said slots being arranged a suitable distance away from the openings 3, and toward the center of the bed plate. The purpose of these slots will presently be fully set forth. Arranged upon the upper face of the bed plate 1 is a mat or cushion 5, the same being constructed of some suitable wood or other fiber or other tissue material which will add to the resiliency of the joint and prevent the heavy concussion and breakage of the parts when the rolling stock passes over the joint. 60

The numeral 6 designates one of the removable side members of the joint. This member 6 includes a flat longitudinally extending foot 7 which is of a size sufficient to be snugly received within the passage or way 70 provided between the flange 2' and the bed plate. The said foot is adapted to contact with the upset portions 2 of the bed plate except where key members, which will hereinafter be fully described, are employed. 75 The side 6 is of a length corresponding with the length of the bed plate 1, and the said side, adjacent its foot is undercut at an angle, as designated by the numeral 8, and the portion thus provided is adapted to engage with the base flanges of the rails R. 80 The central portion or body of the member 6 is constructed of heavy material throughout, and the said member is of a height equaling the height of the rails. The member 6 has its upper inner face longitudinally grooved, as at 9, the said grooved portion corresponding with the cross sectional shape 85 of the head of the rails R, upon this side of the joint, and within which the said portion of the head is adapted to be received. 90

By thus constructing the plate it will be noted that its upper portion is in a plane flush with the plane of the heads of the rails R, and as the said member 6 spans the joint 100 or meeting ends of the rails, it will be noted that the said upper portion thereof provides a bearing surface upon which the outer portions of the wheels of the rolling stock will ride when passing over the joint, and thus 105 the danger of the clipping of the ends of the rails by the wheels of the said rolling stock is entirely overcome.

The member 6 provides the outer side or fish plate for the joint and the inner fish 110 plate or side is designated by the numeral 10. The member 10 has its body portion

angular to agree with the shape of the rails, the vertical member 11 of the said plate engaging with the webs of the rails and underlying the heads thereof, while the second member 12 of the said plate embraces the upper faces and longitudinal edges of the said rails. The member 12 has integrally formed therewith a longitudinally extending portion 13 which is adapted to be received within the passage or way provided between the bed 1 and the flange 2', upon this side of the joint. The outer or longitudinal edge of the foot 13 is adapted to terminate or rather to be spaced a suitable distance away from the upset portion 2 of the plate 1 when the member 10 is arranged upon the plate, this space being, however, filled by the key member 17, hereinafter more fully referred to, when the joint is assembled. The webs of the rails as well as the side members or fish plates of the joint are formed with suitable registering openings for the reception of the usual securing bolts 14 and the nuts 15 for the said bolts. The feet 7 and 13 of the side members of the joint are provided with suitable recesses which register with the recesses or openings 3 in the bed plate and the flange 2' thereof so that when the ordinary securing spikes are driven within the ties the heads of the said spikes may be partially received within the openings 3 of the flanges 2', while the remaining portions of the heads of the spikes overlie the angular lower portions of the removable plates of the joint and the bodies of the spikes engaging with the inner edges of the recessed portions of the feet will force the members 6 and 10 tightly against the longitudinal edges of the rail.

In order to more securely retain the joint rigidly against the rails, I provide a plurality of wedge members 17, the said wedges being forced within the ways or passages 45 between the flanges 2' and the bed 1 at the opposite ends of the bed, and between the outer longitudinal edges of the feet and the removable sides as well as against the outer faces of the spikes. The wedges 17 are provided with threaded stems 18, and the stems are adapted to pass to within the slots 4 and to be engaged by suitable nuts 19 which prevents the accidental removal of the wedges.

In Figs. 5, 6 and 7 I have illustrated a modified form of the joint. The bed plate 1' is similar to that heretofore described, being provided with the upset longitudinal edges 2 and with the inturned flanges 2'. The flanges have their inner faces provided 60 with openings which register with openings in the base plate and in the cushion or mat 3', the said openings being provided for the reception of the securing spikes, and the outer longitudinal edge of the bed plate 65 is notched or formed with slots similar to

the slots 4, and keys and securing bolts therefor are also provided for forcing the removable sides of the joint into tight engagement with the rails R—R. The inner fish plate or side 10' is similar to the side 70 14, but the outer side 6' is centrally and integrally formed with a rail section 18, the inner face of the head thereof being provided with a downturned lip 19 which is spaced a distance away from the web of 75 the said rail section substantially equal to the thickness of the vertical member of the fish plate 14'. The section 6' has its outer face enlarged as at 20, the said enlargement being arranged a suitable distance from the 80 ends of the said member 6', and the enlargement is extended to provide a crest 21 which has its inner face depressed to conform with the faces of the rails with which it is adapted to engage. The crest 85 has its upper portion arranged in a plane with the head of the rail section 18, and consequently also in a plane with the upper faces of the heads of the rails R—R. The removable sides or fish plates are provided 90 with a plurality of openings which register with elongated openings in the webs of the rails R—R, the said openings being adapted for the reception of the usual securing bolts 95 22 and the nuts 23 therefor.

In addition to the wedges 17, I may also employ wedges 24 which are indicated by the dotted lines in Fig. 5 of the drawings. These wedges may be passed through the spike openings and to the rear of the spikes, 100 and after being inserted within the ties a desired distance, the projecting portions of the web may be bent over the heads of the spikes or over the flanges 2' of the bed plate 1 and against the upset portion 2 105 thereof.

From the above description, taken in connection with the accompanying drawings, the simplicity of the construction of my device, as well as the advantages which may be 110 derived therefrom will, it is thought, be perfectly apparent to those skilled in the art to which such inventions appertain without further detailed description.

Having thus described the invention, what 115 I claim is:

1. The combination with rail ends, of a rail joint comprising a bed plate, a cushion member upon the bed plate and upon which the rail ends rest, the said plate having its 120 longitudinal edges formed with inturned flanges, removable side members for the joint, said side members having their lower longitudinal edges provided with feet which are adapted to be arranged beneath the 125 flanges of the bed plate, means for securing the side members of the joint to the webs of the rails, means for securing the base plate to the ties of the road bed, wedge members arranged beneath the flanges of the bed 130

plate and adapted to abut against the feet of the side members of the joint, and adjustable securing means for the wedge members.

2. The combination with rail ends, of a joint comprising a base plate having its longitudinal edges upset and provided with inturned flanges, a cushion mat upon the base plate and upon which the rail ends rest, the outer longitudinal edges of the base plate being notched, fish plates having their lower longitudinal edges provided with feet and adapted to be received beneath the flanges of the base plate, means for securing the fish plates to the webs of the rails, spikes for retaining the fish plates and base plate upon the ties for the rails, wedge members adapted to be arranged between the flanges and the upper face of the base plate and to engage with the longitudinal edges of the feet of the fish plates, said wedges having threaded stems which extend to within the notched portions of the base plate, and nuts arranged within the said notched portions and engaging with the threaded stems.

25 3. The combination with rail ends, of a joint comprising a base plate upon which the rail ends rest, outer and inner angular side members for the plate and adapted to engage with the opposite sides of the rails, the outer side member being provided with an enlarged reinforcing portion which includes a crest, the said crest adapted to engage with the outer faces of the rail ends and to lie in a plane with the top of the rails, secur-

ing elements for the side members and the 35 rails, means embodying spikes for connecting the side members of the joint with the base and to the ties for the rails, and wedging elements for forcing the lower portions of the side members against the edges of the 40 base flanges of the rails.

4. The combination with rail ends, of a rail joint comprising a base plate upon which the rail ends rest, the said plate being formed upon its longitudinal edges with 45 inturned flanges, inner and outer angular side members for the joint, and having their longitudinal edges resting within the flanges of the base plate, the outer angular member having an enlarged outer face which is extended to provide a crest that engages the outer faces of the heads of the rails and lies in a plane with the treads of the rails, the said outer section being centrally formed with a rail section against which the rail 50 ends abut, means for connecting the joint sections with the webs of the rails, means embodying spikes for securing the side members upon the base plate and upon the ties for the rails, and wedge members for forcing 55 the side members of the joint tightly against the edges of the base flanges of the rails.

In testimony whereof I affix my signature in presence of two witnesses.
